(57) **CLAIM**

The ornamental design for a combine left side panel unit, as shown and described.

DESCRIPTION

FIG. 1 is a side view of a combine left side panel unit showing our new design, the broken line showing of the vehicle and ground line being for illustrative purposes only, and forms no part of the claimed design.

FIG. 2 is an enlarged top view of the combine left side panel unit design of FIG. 1.

FIG. 3 is a side view of the combine left side panel unit of FIG. 2.

FIG. 4 is a bottom view of the combine left side panel unit of FIG. 2.

FIG. 5 is a front view of the combine left side panel unit of FIG. 2; and,

FIG. 6 is a rear view of the combine left side panel unit of FIG. 2.
